 graphie m. b. H., Berlin, Germany, a corpora-
 tion of Germany

Application March 19, 1937, Serial No. 131,875
 In Germany March 27, 1936

3 Claims. (Cl. 250—36)

A sawtooth shaped potential is required for the recording of periodically recurring electrical actions by a Braun oscillograph if Lissajous figures which are generally not evaluable without retracing are to be avoided, and the frequency of the potential must be equal to, or be a multiple of, the frequency of the action to be investigated or analyzed. It is convenient also that the frequency of the potential should be easily adjustable. Moreover, with the use of standard Braun tubes in which the pencil strikes about the middle of the fluorescent screen in the non-deflected or quiescent state of the pencil it is very necessary that the sawtooth voltage wave should be symmetric in shape and trend, in other words, it must be free from D. C. components.

My invention in general provides a regenerating oscillating tube arrangement having an oscillatory circuit joined to the anode of said tube, sinusoidal waves generated by the oscillator being fed to a vacuum tube acting as a discharge path for a condenser in which charges are linearly stored and discharged. The condenser resistance combination by means of which the condenser is charged comprises a time constant circuit which is mechanically interlocked with the aforementioned oscillatory circuit so that these two circuits are maintained in a definite relationship each with the other.

My invention will best be understood by reference to the figures in which

Fig. 1 shows one embodiment of my invention, and

Fig. 2 shows another embodiment of my invention.

Referring to Fig. 1 of the accompanying drawing, a vacuum tube 10 has an oscillation circuit 11 connected in the anode thereof, said circuit including the condenser 12 and the choke coil 13. A regeneration (feedback) coil 15 is connected to a condenser 14 which is joined with the grid of the tube 10. A grid leak acts as a leak path for condenser 14. The plate of tube 10 is connected by way of a coupling condenser 17 with the control grid of a tube 18. The latter also has a grid leak 19. In parallel connection with the tube 18 is a condenser 20. The plate and the filament of tube 18 are respectively connected by way of two resistances 21, 22 of like size with the positive and the negative pole, respectively, of a source of D. C. voltage, this source being grounded at a suitable point. In parallel relation to the said tube 18 by way of coupling condenser 23 is the deflector plate system of the

oscillograph tube 24, the deflector plates being earthed by way of resistances 25.

The arrangement shown in Fig. 1 operates in the manner that on the control grid of tube 18, by way of coupling condenser 17, is impressed a sinusoidal potential to ground. When the said potential presents a crest value with reference to the filament of tube 18, flow of grid current will be initiated which sets up the requisite negative grid biasing potential on one side of condenser 17, the latter being caused to leakaway again gradually by way of the resistance 19. The condenser 20 is constantly charged by way of resistances 21, 22, the condenser potential showing a rise proportional to time, when starting from zero potential across condenser 20 or from an initial voltage which is small compared with the source of charge potential. Upon each initiation of discharge in the tube 18, the condenser 20 is discharged through the said tube, down to the value at which the plate current as a result of decline of plate potential becomes interrupted or down to the value when the control grid potential of tube 18 lies again below the lower bend of the plate current grid voltage characteristic. If tube 18 is a grid-controlled gas or vapor type discharge vessel with an arc-like discharge, it is generally possible to produce lower minimum values of potential at the condenser 20, than in a case where tube 18 is of the high-vacuum type. The sawtooth shaped alternating voltage arising across the condenser 20 consists of a D. C. component which arises across the blocking condensers 23 and a symmetric sawtooth component which in major art is operative at the deflector plates of the Braun tube. The resistances 25 moreover have this action that a D. C. voltage possibly set up across the deflector plates as a result of creepage or sneak currents is allowed to leak away.

The frequency of the sawtooth voltage may be regulated in a particularly simple manner by that the setting means for the condensers 12 and 20 are mechanically coupled or interlocked, an end which is attainable in practice by that the rotor parts of both condensers are seated upon one and the same shaft.

In another exemplified embodiment of the invention as shown in Fig. 2 a coupling by the aid of a transformer 26 is used in lieu of the capacitive coupling Fig. 1. The grid leak 19 in this scheme is disposed in parallel relation to condenser 17. As to the rest, both the arrangement as well as the operation thereof are the same as explained by reference to Fig. 1. Also the chance

of coupling the two condensers 20 and 12 is the same as described by reference to Fig. 1.

What I claim is:

1. An apparatus for producing energizing potentials comprising an oscillator, an electric storage element, means for storing a charge in said storage element, a discharge path for said storage element, means for coupling the oscillator to said discharge path, and means for simultaneously varying the storage rate of said storage element and the natural frequency of said oscillator.

5 2. An apparatus for producing energizing potentials comprising an oscillator, an electric storage element, means for storing a charge in said storage element, a discharge path for said storage element, a time constant circuit connected to said discharge path, means for coupling said discharge path and said time constant circuit to said oscillator, and means for simultaneously varying the

storage rate of said storage element and the natural frequency of said oscillator.

3. An apparatus for producing energizing potentials comprising an oscillator having an oscillatory circuit therein, an electric storage element, a discharge path for said storage element comprising a vacuum tube having anode, cathode, and at least one control electrode, the anode-cathode path in said tube forming the discharge path for said electric storage element, means for storing 10 energy in said storage element, a time constant circuit connected in the control grid-cathode circuit of said vacuum tube, a connection between the oscillatory circuit and the time constant circuit, and means for simultaneously varying the 15 natural period of said oscillatory circuit and the storage rate of said storage element.

ROBERT ANDRIEU.
